(57) **CLAIM**

The ornamental design for a mobile phone, as shown and described.

DESCRIPTION

1. Mobile phone

1.1 : Front view of a mobile phone in a closed condition, with the pop-up camera feature retracted

1.2 : Back view thereof

1.3 : Left view thereof

1.4 : Right view thereof

1.5 : Top view thereof

1.6 : Bottom view thereof

1.7 : Perspective view thereof

1.8 : Front view of a mobile phone in a closed condition, with the pop-up camera feature extended

1.9 : Back view thereof

1.10: Right view thereof

1.11: Left view thereof

1.12 : Top view thereof

1.13 : Bottom view thereof

1.14: Perspective view thereof

1.15 : Front view of a mobile phone in an open condition, with the pop-up camera feature retracted

1.17: Left view thereof

1.18: Right view thereof

1.19 : Top view thereof

1.20: Bottom view thereof

1.21: Perspective view thereof

1.22: Front view of a mobile phone in an open condition, with the pop-up camera feature extended

1.23: Back view thereof

1.24: Left view thereof

1.25: Right view thereof

1.26 : Top view thereof

1.27: Bottom view thereof

1.28: Perspective view thereof

1 Claim, 28 Drawing Sheets
